UNITED STATES PATENT OFFICE.

CHARLES A. MEZGER, OF BROOKLYN, NEW YORK, ASSIGNOR TO MINNIE MEZGER, OF BROOKLYN, NEW YORK.

SPARKING PLUG.

SPECIFICATION forming part of Letters Patent No. 700,147, dated May 13, 1902.

Application filed March 25, 1902. Serial No. 99,902. (No model.)

To all whom it may concern:

Be it known that I, CHARLES A. MEZGER, a citizen of the United States, and a resident of the city of New York, borough of Brooklyn, in the county of Kings and State of New York, have invented a new and Improved Sparking Plug, of which the following is a full, clear, and exact description.

The object of this invention is to prevent sooty formations within the cylinder of an internal-combustion engine from accumulating around the sparking points in such a manner as to short-circuit the igniter.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is an exterior view of the sparking plug. Fig. 2 is a longitudinal section thereof. Fig. 3 is a section on the line 3 3 of Fig. 2, and Fig. 4 is a section on the line 4 4 of Fig. 2.

a indicates the plug proper, which is formed of metal and screwed or otherwise fastened into the walls *b* of the cylinder, as will be understood.

a' indicates one of the sparking points, which point is carried by the plug *a* within the cylinder. The other sparking point is formed by a rod *c*, of suitable material, having nuts *c'* at its outer end for the connection of the wire thereto. In the inner part of the plug *a* is formed a chamber *a*², communicating with the cylinder, and in the outer part is formed a chamber *a*³, opening at the outer end of the plug. These chambers are connected by a reduced central passage *a*⁴.

Through the passage *a*⁴ extends a tube *d*, of hard insulating material, the tube having an annular shoulder *d'*, bearing against the inner end wall of the chamber *a*². Beyond the shoulder *d'* the insulating-tube *d* is extended to form a tubular shell *d*², which extends through the chamber *a*², slightly inward beyond the same. The rod *c* passes through the tube *d* and through the tubular shell *d*² thereof and projects inward beyond this shell opposite the sparking point *a'*. On the rod *c* is formed an

annular shoulder *c*², and this shoulder bears against an internal shoulder *d*³ on the tube *d* at the outer extremity of the shell *d*² thereof.

e indicates a porcelain or other non-conducting cap, which is set in the chamber *a*³, and against which the pressure of the nuts *c'* is exerted, the rod *c* passing through the cap *e*.

f and *f'* indicate gaskets, of yielding non-conducting material, set between the cap *e* and the plug *a* and between the exterior flange *d'* and the cap to keep the parts properly spaced and to prevent the unyielding pressure of the nuts on the porcelain or other frangible parts.

When the nuts *c'* are screwed up tightly, the collar or shoulder *c*² on the rod *c* is forced against the shoulder *d*³ of the tube *d* and this tube is drawn firmly outward, thus pressing its exterior shoulder *d'* against the gasket *f* and through the medium of this gasket against the inner wall of the chamber *a*² in the plug *a*. By means of the shell *d*² an annular barrier is formed completely around that part of the sparking point *c* which is exposed to the sooty accumulation within the cylinder, this shell lying in the chamber *a*³ and being spaced from the walls thereof and from the sides of the sparking point *c* and leaving only the extremity of said sparking point exposed, so that it may have the proper coaction with the sparking point *a'*. It will therefore be seen that in order that the electric current may pass between the contact-points in any other manner than in the way in which it is intended this current will have to move along the outer side of the shell *d*² and thence over the edge and inward along the inner side of the shell to the collar or enlargement *c*². This makes a long path, and owing to such length and to the poor conducting qualities of the soot the above-mentioned short circuit is prevented. Were it not for this shell, arranged in the manner explained, the current could pass readily from the walls of the chamber *a*² across to the rod *c*, and short-circuiting would therefore be of frequent occurrence. It is this disadvantage that my invention overcomes.

Various changes in the form and details of my invention may be resorted to at will without departing from the spirit thereof. Henceo

I consider myself entitled to all forms of the invention as may lie within the intent of my claims.

Having thus described my invention, I 5 claim as new and desire to secure by Letters Patent—

1. The combination of a chambered plug having a sparking point thereon, an elongated conducting member forming the second sparking point and projected through the chamber and extending adjacent to the sparking point, and a tubular shell arranged in the chamber of the plug and spaced from the walls thereof and from the sides of said elongated member 15 forming the second sparking point, for the purpose specified.

2. The combination of a chambered plug having a sparking point thereon, an elongated conducting member projected through the 20 chamber and extending adjacent to the sparking point, a tubular insulating-shell arranged in the chamber of the plug and spaced from the walls thereof and from the sides of said elongated member forming the second sparking point, for the purpose specified, an insulating-tube at the base of the insulating-shell, and means for holding the said elongated conducting member snugly within the shell and tube.

3. The combination of a chambered plug having a sparking point thereon, an elongated conducting member projected through the chamber and extending adjacent to the sparking point, a tubular shell arranged in the 35 chamber of the plug and spaced from the walls thereof and from the sides of said elongated member forming the second sparking point, for the purpose specified, an insulating-tube at the base of the said insulating-shell, and means for holding the said elongated 40 conducting member snugly within the shell and tube, said means comprising an in-

sulated cap bearing against the plug and a nut working on the outer end of the said elongated conducting member.

45

4. An electric igniter, comprising an elongated member forming a sparking point, and an insulating-shell inclosing the major portion of the exposed part of said elongated member, the said shell having an open space 50 around its outer side and between its inner side and the said elongated member.

5. The combination of a plug proper having a chamber therein and a reduced passage leading therefrom, an insulating-tube placed in 55 the said passage and having a shell-like extension projected into the chamber of the plug and spaced from the interior walls thereof, and a rod projected through the tube and through the shell, said rod being spaced from 60 the inner walls of the shell, for the purpose specified.

6. The combination of a plug proper having a chamber therein and a reduced passage leading therefrom, an insulating-tube placed in 65 the said passage and having a shell-like extension projected into the chamber of the plug and spaced from the interior walls thereof, a rod projected through the tube and through the shell, said rod being spaced from 70 the inner walls of the shell for the purpose specified, and being formed with an enlargement engaging a shoulder at the outer end of the shell, and means for exerting an outward pressure on the rod to hold the parts snugly 75 engaged.

In testimony whereof I have signed my name to this specification in the presence of two subscribing witnesses.

CHARLES A. MEZGER.
